FIG. 1.

FIG. 2.

FIG. 3.

INVENTOR
Edward N. Tunick

UNITED STATES PATENT OFFICE

104,825

DESIGN FOR A DRESS ENSEMBLE

Edward N. Tunick, New York, N. Y.

Application April 29, 1937, Serial No. 69,029

Term of patent 3½ years

To all whom it may concern:

Be it known that I, Edward N. Tunick, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a front view of the dress unit of the dress ensemble shown in Figure 1.

Figure 3 is a fragmentary view of the rear portion of the dress unit of the dress ensemble.

The rear portion of the cape unit is conventional.

The bottom edge portion of the skirt is identical in both the front and rear portions, excepting the contrasting portion, as indicated in the stippled area of the skirt portion shown in Figure 2, which has its center point extending to the bottom edge of the skirt.

The characteristic feature of my design resides in the combination of a dress of the instant configuration having contrastingly colored skirt bands as shown and described, in association with a hooded cape as shown, said cape matching the lower skirt band in color.

I claim:

The ornamental design for a dress ensemble, substantially as shown, and described.

EDWARD N. TUNICK.
